Patented June 4, 1929.

1,715,485

UNITED STATES PATENT OFFICE.

GILBERT C. WHITNEY, OF NEW YORK, N. Y.

RAILWAY-TRAFFIC-CONTROLLING SYSTEM.

Application filed March 25, 1926. Serial No. 97,282.

This invention relates to railway signaling systems in general; with particular reference to combined types of "speed restricting" or "closing in" and "train stopping" systems; and specifically provides a novel means for "enforcing the caution indication", for "enforcing the proceed indication" and for clearing the wayside automatic train stopping mechanism of the aforementioned systems of automatic block signaling on electrically propelled railway systems and by virtue of my superposed control system.

This application is a continuation, in part, of my co-pending applications Serial Nos. 15 33,731 and 40,789, and Patent No. 1,596,222, dated August 17, 1926, for train indication systems.

By way of explaining the terms—"enforcing the caution indication"—"enforcing the proceed indication"—it may be stated that; whereas present signaling systems of this type provide for the approaching train to "advance the stop or caution indications" or move the stop signal ahead (as it is popularly termed in the art) provided the approaching train speed is reduced; my invention, as hereinafter described, provides for "advancing of the stop and caution indications" by reduced speed on the part of the approaching train and also provides that the "stop and caution indications will be moved back" if there is any violation in the speed of approach after reduced speed, on the part of the approaching train has given effect to "advancing the stop or caution indications".

The phrases "move the stop signal ahead"; "advancing the stop indication"—"set (the signal) ahead"—and the phrases "move the caution back"—"move the proceed indication back"—"set (the signal) back" etc., are to be understood in the sense, as being carried into effect by virtue of automatic change in circuit arrangements and not that any actual physical movement of any given signal from its location takes place. By further definition the phrase "set ahead" is to be understood as change from the stop indication to the caution indication or from the caution indication to the proceed indication—in other words, the aspect is changed to the next less restrictive aspect; and the phrase "set back" is to be understood as change from the proceed indication to the caution indication or from the caution indication to the stop indication—in other words, the aspect is changed to the next more restrictive aspect.

The appropriate change in the wayside automatic stop in each case, of course, will change to correspond with change in aspect.

The need for this invention will be apparent when it is appreciated that on existing systems, of this type, which have no means for insuring a continuance of the required reduced speed, an excess amount of territory must be included in the control of the signal in question to make definitely certain that safe conditions prevail even though the speed of the approaching train should be increased unlawfully. The inclusion of excess territory in the control operates to reduce the train capacity of the railroad and my invention is directed mainly to the point of providing the absolute capacity and safety—or, in case full capacity is not the desideratum, then my invention will operate to produce the required capacity with full safety and with less apparatus and consequently less cost than is required by existing systems.

The general objects of my invention, herein disclosed, are to facilitate the safe operation of railway trains; to provide simple and effective means for restricting train speed and thereby permit closer headway with consequent increased use of a given track; to provide means for enforcing the proceed and caution indications; to provide for clearing of the wayside automatic train stopping mechanism under emergency operation; to avoid the ill effects of broken rails and wires which in existing systems cause false clear failures of time controlled signals or other devices in the advance; and to make my invention readily applicable to existing block signal systems and with no change in the make-up of existing train-carried co-operating parts at present in service on trains of rapid transit character; and with minimum change and expense in the existing systems of this type of signaling; and other objects will appear as the specification progresses.

I have illustrated my invention particularly as applied to electric railroads wherein the trains are operated by electric motors deriving current from a third rail or other conductor other than the track rails, but it is to be understood that an overhead trolley wire may be substituted for what is, strictly speaking, a third rail, and also that the propulsion current (meaning the characteristic train motor operating current) may be either

direct or alternating current without departure from my invention.

In describing my invention I will refer to the accompanying drawing, wherein a series of consecutive blocks of an automatic block signaling system are identified by the reference characters 1, 2, 3, 4 and 5. A portion only of the block preceding block 1 and of block 6 is shown.

- 10 At the entrance to each block I show a wayside light-type signal 1¹, 2¹, 3¹, 4¹, 5¹ and 6¹. Also approximately at the entrance to each block I provide an automatic stop and incorporated in each block section I provide the usual and well-known track circuit and signal control circuits for governing the movement of trains over the controlled territory. For the purpose of simplicity and clarity only, I have only shown the apparatus 20 and circuits complete for block section 2 but I desire it to be understood that each block section will be comprised and constituted substantially similar, except as modified by the requirements in each installation and as 25 pointed out hereinafter, and it is believed, therefore, that a full explanation as to block section 2 and associated apparatus and circuits will suffice to clearly portray this invention.
- 30 The track rails, on which the trains run, are insulated from each other and one rail 7 of the territory is bounded continuously through the territory for the return of the propulsion current, as hereinafter explained.
- 35 The other rail 8, characteristically known in the art as the signal rail, is sectionalized by means of track rail insulated joints 9, substantially at each block signal location, and the track sections thus formed, together 40 with the corresponding portions of track rail 7, constitute the track rail portions of the well-known so-called "single rail track circuit". Comprising and completing the track circuit, a transformer 10 is shown connected to the track rails 7, 8 by means of track wires 11, 12, resistance 13 and fuse 14—transformer 10 being the medium, when energized via wires 15, 16 from power wires 17, 18, connected to the source of power 19, 45 by which appropriate current supply, when a train is not present, is transmitted over track rails 7 and 8 (for the respective section) to track wires 20, 21, fuse 22 and resistance 23 to winding 24 of track relay 2^T.
- 50 Winding 25 of track relay 2^T receives energy via wires 26, 27, connected to wires 15, 16, thence from source 19 via power wires 17, 18, as will be appreciated. Thus far the track circuit is the well-known single rail alternating current track circuit wherein most of the energy required for the operation of the track relay 2^T is supplied locally and only a small part or activating current is transmitted over the track rails. It is to be understood, that the track circuit, as above,

is constituted and arranged so that the winding 24 of relay 2^T will be shunted by train car wheels on the respective track circuit and whenever said shunt occurs the track relay for that section will be open, thus 70 providing for the automatic operation of the usual block signal and automatic stop system, as will be appreciated.

Each block signal 2¹, etc., as shown, is comprised of red, yellow, and green lenses 75 and contains a source of illumination for each lens, when appropriately controlled in the usual manner, whereby the customary aspects, red, yellow, and green, conveying respectively the Stop, Caution, and Proceed 80 indications (as to the occupancy of the advance territory) are transmitted to the motorman.

Associated in the control of the block signal and automatic stop, I have shown a home relay 2^H, a distant relay 2^D and a time relay 94, in addition to the above mentioned track relay. The terms, home relay, distant relay etc., are characteristic terms well-known in the art—the home relay being that device which, when appropriately energized, brings about the display of the herein mentioned caution (yellow aspect) indication with coincidental changes in the automatic stop—the distant relay being that device which, when appropriately energized, brings about the display of the herein mentioned proceed (green aspect) indication with co-incident changes (if required) in the automatic stop—and the time relay being a device which, when appropriately controlled in accordance with train movement (usually in the approach territory), causes a predetermined change in the character of the signaling and automatic stop systems, as hereinafter pointed out in detail. The characteristic representation of the relays is in the conventional manner well-known in the art and it is to be understood that wherever the terms—energized contact and back contact are used it is meant that the instant contact is closed when the relay, which operates that contact, is deenergized and that wherever the terms—energized contact and front contact are used it is meant that the instant contact is closed, when the relay, which operates that contact, is energized even though no energy be flowing in the circuit which includes said instant contact.

The home relay 2^H is energized and controlled in the usual manner over the circuit which may be traced as follows: from the source of energy 19 power wire 17 wire 28 contact on track relay 6^T for block section 6 wire 29 contact on track relay 5^T (when closed) (this contact is shown open because of the presence of a train in block section 5) wire 30 contact on track relay 4^T wire 31 contact on track relay 3^T wire 32 contact on track relay 2^T thence via wire 33 to winding 120 125 130

34 wire 37 wire 16 to power wire 18 back to the source of energy 19. The home relay is also energized by virtue of winding 35 connected via wires 36, 37 to wires 15, 16, to power wires 17, 18, to the source of energy 19, identically as described in connection with winding 25 of track relay 2^T. The relay 2^H with the windings 34 and 35 constitute one form of the well-known two-element line relay wherein most of the energy required for its operation is supplied locally and only a small current is transmitted over the line circuit, just traced. It is to be understood, that unless both windings 34 and 35 are energized, the energized contacts, operated in response to an energized condition of the relay 2^H, will be open and the associated contacts will be closed. As shown, home relay 2^H is deenergized because the line circuit is open at the contact on track relay 5^T, because of the train occupying block section 5.

The distant relay 2^D is energized and controlled in the usual manner over the circuit which may be traced as follows: from source of energy 19 power wire 17 wire 38 contact on 3^H (when closed) (this contact is shown open because home relay 3^H is deenergized due to the line circuit being open at contact on 5^T on account of the presence of a train in block section 5) wire 39 contact on home relay 2^H (when closed) wire 40 winding 41 wire 44, thence via 16 to power wire 18 back to the source 19. The distant relay 2^D is also energized by virtue of winding 42 connected via wires 43, 44 to power wires 17, 18 to the source of energy 19, identically as described in connection with windings 25 of 2^T and 35 of 2^H. Without further description it will be apparent that distant relay 2^D is of the same form as 2^H and it is to be understood, that unless both windings 41 and 42 are energized the energized contacts, operated in response to an energized condition of relay 2^D, will be open and the associated contacts will be closed. As shown, distant relay 2^D is deenergized because the line circuit is open at the contacts on 3^H and 2^H, because of the train occupying block section 5.

The display of the red, yellow, and green aspects, which convey the stop, caution, and proceed indications (respectively) to the approaching train, is by virtue of the functioning of the track relay, the home relay, the distant relay, (the control circuits of which relays have been explained) and under certain conditions the time relay, the control of which will be explained herein after.

The control circuits of the signal proper will now be explained, and with signal 2¹ as the basis (it being understood that signals 1¹, 3¹, 4¹, etc., are similar).

65 The illumination for the display of the

red aspect is obtained by virtue of energy flow via the following circuits: from source 19 via power wire 17 wire 15 wire 45 deenergized contact 46 (when closed) on track relay 2^T, thence via wires 47, 48, direct to the lamp R, thence via wires 49, 50, 51 to wire 16 to power wire 18 back to the source 19 and, therefore, whenever block section 2 is occupied by a train or for any other reason track relay 2^T is open, the red aspect will be displayed, giving the stop indication at signal 2¹—an additional circuit for the red aspect may be traced as follows: from source 19 via power wire 17 wire 15 wire 52 deenergized contact 53 (shown closed) on home relay 2^H, thence via wire 48 to the lamp R and, thereafter, back to the source 19 as above explained, and, therefore, whenever any block section, or part of any block section, within the control of home relay 2^H is occupied by a train or for any other reason any track relay, within said control, or the home relay 2^H is deenergized, the red aspect will be displayed giving the stop indication at signal 2¹, except as hereinafter provided,— 90 an additional circuit is provided for the red aspect which may be traced as follows: from source 19 via power wire 17 wire 77 and 83 to contact 84, on the stop mechanism S, (closed, as shown, when tripper arm 63 is in 95 the tripping position) thence via wire 85 to the lamp R and, thereafter, as before. The purpose of this last mentioned additional circuit is to insure that at any time the tripper arm 63 is in a tripping position a red aspect (stop indication) will be displayed by signal 2¹.

The illumination for the display of the yellow aspect is obtained by virtue of energy flow via the following circuit: from source 19 via power wire 17 wire 15 wire 52 energized contact 53 (when closed) on home relay 2^H via wire 54 deenergized contact 55 (when closed) on distant relay 2^D thence via wire 56 direct to lamp Y, thence via wires 49, 50, 51, 16, and 18 back to the source 19 and thus it will be evident that the yellow aspect (caution indication) cannot be displayed unless all of the territory within the control (either the long control or the short 110 control as hereinafter provided and explained) of relay 2^H be unoccupied by a train and the signaling system (herein so far described) is functioning properly.

The illumination for the display of the green aspect is obtained by virtue of energy flow via the following circuit—from source 19 via power wire 17 wire 15 wire 57 energized contact 58 (when closed) on distant relay 2^D, thence via wire 59 wire 60 contact 61 (when closed) on home relay 2^H, thence via wire 62 direct to lamp G and, thereafter, via wires 49, 50, 51, 16, 18 back to the source 19 and, inasmuch, as the control circuit for distant relay 2^D is via energized 125

contact (when closed) on home relay 3^H, it will be evident that the green aspect (proceed indication) cannot be displayed unless all of the territory within the control (except as hereinafter provided and described) of both home relays 2^H and 3^H be unoccupied by a train and the signaling system, herein so far described, is functioning properly.

10 The automatic stop mechanism, as illustrated, is of the type which provides for a wayside tripper arm positioned to co-operate with a co-acting tripper arm on the train (when the conditions with respect to the continued movement of the train require that the train brakes be operated) and positioned, by means hereinafter described, so that there will be no co-acting to interfere with said train movement if the conditions in the advance territory are suitable for the train to continue, and while I have shown and will describe the operation of said automatic stop mechanism as being of the electric control, electric motor operated type I desire it to be distinctly understood that I do not limit myself to this type, in fact I may use an electrically controlled, pneumatic or hydraulic means for operation, or I may dispense entirely with all means which requires tripper operation and use the inductor type with corresponding changes in the co-acting train carried equipment.

15 The automatic stop and mechanism S is shown in the tripping position (that is, the tripper arm 63 is in the vertical position, because of the control and operating circuits being incomplete due to the presence of the train in block section 5) and it is to be understood that when in this position an approaching train will have its brakes automatically operated if, and when, said train moves past block signal 2¹. When the tripper arm 63 is not in the tripping position it is in what is termed the clear position (represented by the dotted (horizontal) position). The controlling circuits will now be described. Adjacent the stop S I show, representatively, the tripper arm clearing motor C and the tripper arm holding means H, and adjacent thereto are shown four contacts, 64, 65, 66, and 84, of which contacts 64, 65, and 66 are involved in the working of the stop arm 63 and contact 84 is involved in the working of the signal system, and it is to be understood that the contacts 64 and 66 (shown open) are closed when the tripper arm 63 is in the clear position and that the contacts 65, and 84 (shown closed) are open when the tripper arm 63 is in the clear position. Contact 84 is operated by the stop operating mechanism and is so adjusted that, when the tripper arm 63 is in a tripping position to engage with the car-carried tripper, a circuit is established to insure that

the red aspect R (stop indication) is displayed by signal 21, as hereinbefore explained. The clearing of the tripper arm 63 is brought about by virtue of energy flow in the circuit which may be traced as follows: from source 19 via power wire 17 wire 15 wire 52 contact 67 (when closed) on home relay 2^H, thence via wires 68 and 62 direct to contact 65 on the stop operating mechanism S clearing motor C wire 70 wires 50, 51, 16, and 18 back to the source 19 and it will be understood that when the circuit, just traced, is completed by the closing of contact 67, due to the clearing of home relay 2^H, the tripper arm 63 will be operated to the clear position and contacts 64, 65, 66, and 84 will change, as previously explained. With the changing of contacts 65 and 64 (64 closing before 65 opens) the holding device H is energized to retain the tripper arm 63 in the clear position with only a fraction of the power necessary to the clearing operation. The holding circuit, under these conditions, is via contact 64 (when closed) jumper wire 71, holding device H thence via wire 72 to wires 50, 51, 16, 18, back to the source 19. An additional clearing circuit is provided and which may be traced thus: from source of energy 19 via power wire 17 wire 15 wire 57 contact 73 (when closed) on distant relay 2^P wire 74 wire 69 and thence direct through the clearing circuit previously traced. The reason for this last traced clearing circuit is to provide for emergency operation of the stop, as herein-after described. Owing to the fact that the clearing and holding circuits, as above traced, would be opened by the passage of a train into block section 2 it is necessary that (as shown) means be provided to prevent the tripper arm 63 from going to the tripping position and engaging with a rear car-carried tripper arm and I provide for this by the stop retaining circuit which may be traced thus; from source 19 via power 17 wire 15 wire 45 deenergized contact 75 (when closed) on track relay 2^T, thence via wire 76 direct to contact 66 (closed in the clear position) to holding device H and thence via wires 72, 50, 51, 16, 18 back to the source 19 and thus it will be evident, that the automatic stop, having been cleared by the regular operation of the signal system, will be retained in the clear position as long as any part of the train is in block section 2; or, in other words—as long as contact 75 on track relay 2^T is closed. As a matter of fact, as long as contact 75 is closed and stop retained in the clear position (even though a train be occupying block section 2) just so long the control circuits for the stop, operating in connection with signal 1¹ would be open and hence a following train would be tripped at the entrance to block section 1, or farther in the rear according to the control of the 130

approach signals, as will be appreciated. The tripper arm 63 assumes the stop (vertical) position by virtue of compression springs or a counter weight (not shown) 5 customary and well-known in all forms of machines of this type.

It frequently happens that, owing to derangements in the regular operation of the signaling system, or, for abnormal closing 10 purposes, it is desirable to permit a train to pass a stop signal and means must be provided to clear the automatic stop mechanism so that the train can proceed without being tripped and for this I provide 15 emergency key K so located that the motorman, after stopping his train, may operate the key K, thus completing the circuit from source 19 via power 17 wire 77 via key K (when closed) thence via wires 78 20 and 79 to winding 41 of distant relay 2^D to wires 44, 16, 18, and back to the source 19 and the momentary flow of current in this circuit, before the motorman releases the key K, energizes said relay 2^D causing the 25 closing of contact 58 whereby a stick circuit from source 19 via power wire 17 wires 15 and 57 contact 58 (when closed) wires 59 and 80 to contact 81 on track relay 2^T wire 82 thence via the pick-up circuit wire 79 to 30 winding 41 and thereafter over the return circuit wires 44, 16, 18, back to the source 19 and it will be evident that said relay 2^D will remain energized until the stick circuit is opened at contact 81 on track relay 35 2^T due to the train having entered block section 2. Following the emergency operation of distant relay 2^D, the hereinbefore described clearing circuit, via the distant relay 2^D control, is established, resulting in 40 the clearing of the tripper arm 63 and thereafter the retaining circuit is effective, as previously described. As a matter of practice, it would be undesirable to have the proceed (green aspect) indication given 45 during this emergency operation, and the circuit, hereinbefore traced, for the energizing of the green aspect (lamp G), is open by virtue of contact 61 on home relay 2^H being open and, due to home relay 2^H being 50 deenergized, the circuit for the energizing of the red aspect, hereinbefore traced via contact 53 and wire 48 is complete, thus providing for the display of the red aspect for said emergency operation.

55 The train carried means which provides for the actual stopping of the train, in the event that any attempt is made to pass an automatic stop tripper arm when in the tripping position, contemplates the use of 60 the usual and well-known air-brake system wherein the manipulation of the car-wheel brakes is caused by increased air-pressure in the brake operating cylinders which increased air-pressure is governed in accordance 65 with variation of air pressure in the

governing train line and the variations of air pressure in the train line are made effective, in ordinary operation, by the motorman's operation of the air-brake controller. An additional outlet in the governing train 70 line is provided and equipped (as illustrated) with a normally closed trip-cock 86 on which is mounted tripper 87 which is normally positioned in the vertical position. When tripper arm 87 is in the vertical 75 (tripping) position, it is to be understood that, the train line is closed and the brake application cylinders responsive only to the control of the motorman's brake controlling handle, but that in the event of any attempt 80 being made for the train to pass a signal displaying the stop indication, except as hereinbefore provided, the automatic stop tripper arm 63 being in the tripping position, the car-carried tripper arm 87 will 85 come into contact with tripper arm 63 whereupon tripper 87 will be moved out of the vertical position to one or the other of the positions (shown dotted and depending upon the direction in which the train is 90 moving as to which position results) whereby the train line is opened to "exhaust" and, as is well-known and readily understood in the art, increased pressure is brought about in the brake application cylinders thus providing for an entirely automatic application 95 of the brakes. It is to be understood that the car-wheel brakes cannot be released until the tripper arm 87 is manually restored to the vertical position to close the train 10 line. It will be understood that I may dispense with the stop-cock type of car-tripper and arrange so that tripper 87 opens an electric circuit to effect the operation of an electro-pneumatic valve whereafter the 10 braking operation is as before and also that, in the event of using an inductor type of tripper device at the signal location, the corresponding counterpart car-carried equipment would be provided and arranged 11 to effect the operation of the electro-pneumatic valve above referred to. The restoring of the train brake system may also be carried into effect automatically by the sequential operation of car-carried devices, 11 but only after the train has been brought to a stop.

The track and circuit, signal and circuits, automatic stop mechanism and circuits, and train brake system design outlined above 12 are intended simply as a structure and I make no separate claims of invention in connection therewith nor do I limit myself in scope to said design—it is shown only to provide a basis for suitably illustrating and 13 disclosing my invention.

This invention consists in connecting the primary winding 88 of transmitter transformer (inductive coupling) 89, in multiple with resistance 13 in the energy supply to 14

the track circuit (shown in connection with the track circuit for block section 1) and so that a part of the current flowing to winding 24 of track relay 1^r passes through said 5 winding 88. Inductively coupled to winding 88 is shown secondary winding 90 and the current induced therein is carried over wires 91 and 92 to winding 93 of time element device relay 94. Winding 95 of relay 10 94 receives energy via wires 51 and 96 connected to wires 15, 16 and thence via power wires 17, 18 from the source 19. Winding 95 and the included circuit, last traced, is provided on this time relay for the same 15 purposes, as hereinbefore explained, viz, to avoid the necessity of carrying all of the energy required for the operation of the time element device over the control circuit and to facilitate the operation under certain conditions of track circuit installation, as hereinafter described. When the track section 20 (1) is not occupied by a train, winding 24 and resistance 23 are included in series directly in the circuit receiving current which 25 passes from transformer 10 and through winding 88, but when a train enters the track section (1) the wheels of the train, having negligible resistance, as compared to winding 24 and resistance 23, shunt out said 30 winding and resistance, and more current flows from transformer 10 via winding 88. The increased rate of current flow causes an appropriate increase in the current induced 35 into the circuit which includes secondary winding 90 and winding 93 of time element relay 94 and which increased induced current energizes winding 93 sufficiently so that, in co-operation with winding 95, operation 40 of time element relay is produced, eventually to close contact 97 for the control of circuits, as hereinafter described. When the track section (1) becomes unoccupied, winding 24 and resistance 23 of relay 1^r are restored in 45 full effect in the track circuit for track section 1 and due thereto less current flows via winding 88 with appropriately lessened induced current flow to winding 93 of the time element device 94 at which time said relay 94 is restored to its original condition and, 50 with said restoration, the appropriate changes in circuits controlled by said relay—it being understood that when the track section (1) is unoccupied by a train, the current flow to winding 93 is neither sufficient 55 to hold contact 97 closed, nor to close it if it is open.

The time element device relay 94 is of the slow-acting or delayed-action type; that is to say, a predetermined interval of time is required for the closing of the contact 97 following the appropriate energizing of winding 93. Such delay-action relays and devices are well-known in the art and I do not limit myself to any particular type of

such relay or device. It is well-known that, 65 by means of a variable counterweight, or variable distance through which a weight is moved, the time required for the closing of the contact 97 by the device may be any thing predeterminedly desired, within reasonable limits—it being understood that, when such relays or devices control slow closing contacts, the opening of said contacts is at the start of the restoring stroke and by virtue of the return movement of the counterweight. The time element or delay action is, of course, that part which retards or 70 withholds the closing of the appropriate contacts and which, as shown, is controlled by relay winding 93. The time element function, described above as being carried into effect by a counterweight, may be a dash-pot. I desire to point out at this time, that the specific control of time element device 94 is by virtue of the current flow through the 75 train wheel shunt and that I do not limit myself to the use of transmitter transformer 89 and/or winding 95 and that I may control the time element device by another relay, with or without transmitter transformer 89, when the characteristics of the particular 80 track circuit and propulsion return current flow are unsuited to the control of the time element device, as shown—more especially 85 with reference to the influence control by the 90 propulsion return current flow, as described 95 hereinafter.

I have previously referred to the track section (1) being occupied and it will be understood that the train, represented by car-wheels 98—98^a, electrically connected by axle member 99, is equipped with propelling electric motor 100, a controller 101 for said motor, and third rail sliding contact 102 which contact is in continuous contact with third rail 103. The propulsion current is supplied by generator G to the third rail 103 by means of wire 104 and the return circuit from the track rails is via 105 (wire) connected to track rail 7. It will be understood, 100 that the bonds connecting the several track rails comprising track rail 7 of the entire territory are of suitably heavy design appropriate to the purpose. The operation of the train is as follows: To start the train, 105 controller 101 is moved into engagement with contact 101^a and propulsion current then flows from generator G via wire 104, third rail 103, sliding contact 102, thence via contact 101—101^a (now closed), motor 100, 110 connecting member axle 99, car-wheels 98—98^a, and returning thence over track rails 7 and 8 to generator G via wire 105 and rotation of the motor is produced, resulting 115 in movement of the train, as will be appreciated. The train operating means, just described, forms no part of my invention, except that operation of the controller 101 and 120 125

propulsion return current flow are involved in combinations to produce and influencing the control of time-element device 94.

I have stated that the return of the propulsion current from the motor 100 is via track rails 7 and 8 and it will be apparent that, since track rail 8 is separate from track rail 7 at the generator end of the track circuit (and also at the other end of the track circuit), all propulsion return current flowing in track rail 8 must flow via the secondary circuit of transformer 10 which includes wires 11, 12, fuse 14, and resistance 13 with winding 88 of my transmitter transformer 89 in multiple with resistance 13, or via the circuit wires 20, 21, fuse 22, resistance 23, and winding 24 at the other end of the track circuit.

Particular reference is made, at this time, that, given a resistance and an impedance (winding 88 constitutes an impedance) in multiple and arranged in a circuit wherein alternating current and direct current may flow, the resistance tends to favor the passage of the alternating current, and the impedance tends to favor the passage of the direct current, and thus is created a normal automatic bias to the direct current propulsion return current flow, (which does not obtain at the relay end of the track circuit) and which bias enhances the propulsion return current flow effect, and, therefore, controller 101, control, influence on the regular signal current operation of any circuit, and therefore, any device incorporated in said circuit, which is inductively coupled to winding 88.

From the foregoing it will be evident that, the return propulsion current actually flows in the circuit with the alternating current from transformer 10 and both currents flow in the winding 88 of transmitter transformer 89 and in amounts comparable to the conditions of the circuits at any particular time.

The influence of the propulsion current flow via winding 88 (as reflected in this particular invention) is for the purpose of modifying the operation of time element device 94, if and when the propulsion return current flow exceeds a predetermined amount. The modification may be arranged: (a) to cancel a previous operation of the time element device which previous operation was brought about by the regular shunting of the track circuit, as hereinbefore explained; and (b) to withhold a regular operation (by signal current) of said time element device 94 if the power current flow through the controller 101 (and therefore through motor 100), while the train is occupying the track section (to which the time element device is inductively coupled), is greater than a predetermined amount. The desired influence of the propulsion current on time element device 94 is brought into effect by

virtue of change in the degree of magnetization and wave shape of the flux wave in the magnetic circuit of transmitter transformer 89 (when transformer 89 is used, otherwise the change influences the wave 70 shape and degree of magnetization generated by winding 93 of device 94), as hereinafter explained.

I have previously explained that, when the track section (1) was unoccupied, the current flow via winding 88 of transmitter transformer 89 was insufficient to induce the required amount of current flow, in the circuit including winding 90, for the operation of time element device 94 and that 80 when the track section was occupied by a train the increased rate of signal current flow via winding 88 was sufficient to induce the required amount of current flow in winding 93 for the operation of said time element 85 device 94. The operation here referred to makes use of transmitter 89 in the form of an ordinary transformer consisting of the customary primary winding 88 and secondary winding 90 mounted adjacent on an 90 (iron) magnetic circuit (not specifically shown) and the action is in accordance with the well-known and understood laws on mutual induction wherein the flow of an alternating current in the primary winding 95 88 generates a magnetic flux in the magnetic circuit which flux substantially follows, in wave shape and character, the generating (primary) current which produces it and wherein the current flow induced in the circuit which includes the secondary winding 90, by virtue of the magnetic flux, substantially follows, in wave shape and character, the flux which produces it, and, therefore, the values of the primary and secondary 105 currents and the magnetic flux (below the knee of the magnetization curve, so-called) are substantially interdependent, proportionate and automatic, according to the conditions of design.

I arrange the design of transformer so that, with the track section unoccupied, the flux density in the magnetic circuit is low and which automatically increases with normal increase in primary current (due to a 115 train on the track section) to a point well up on the knee of the magnetization curve (so-called). There are two reasons for this, one of which is—so that the variation in induced current, supplied to winding 93 of 120 time element device 94, as between a train at one end or the other end of the track section, will be small—and the other reason is, that saturation of transformer 89 magnetic circuit, by a predetermined amount of 125 return propulsion current, for control, purposes, as hereinafter explained, is more readily obtained. Owing to the fact that time element device 94 operates on the induction motor principle, it, of course, will be 130

apparent that the variation in current flow, as between a train at one end or the other of the track section, will not materially affect the time factor of time element device 94.

- 5 The propulsion return current from motor 100, which is controlled by controller 101, has been described to flow via winding 88 when the train is in the respective track circuit. The amount of propulsion current 10 flowing via winding 88, of course, is proportionate to the conductivity of the two paths (one path via track rail 7 direct and the other path via track rail 8 wire 12 fuse 14 winding 88 (with resistance 13 in multiple) 15 transformer 10 and wire 11 to track rail 7) and winding 88 is proportioned to permit a predetermined amount, as desired, of said propulsion current return to flow therethrough without affecting the regular operation 20 of time element device 94. When the predetermined amount is exceeded the effect of said excess is to saturate the magnetic circuit of transformer 89. This saturation, in the case of the propulsion current being direct current, permanently (as long as said propulsion current flow persists) lines up substantially the entire flux in one direction 25 with the net result that the flux is non-responsive to the track circuit operating current, with final result that the induced current flow via winding 93 is reduced below its operating requirements and if the time element device 94 were energized (and contact 97 closed) deenergizing to a certain extent 30 would obtain and contact 97 would open, and again, if time element device 94 were deenergized (so to speak) and contact 97 open, the contact would remain open due to the fact of the presence of propulsion return 35 current in the predetermined amount saturating transformer 89 and offsetting the normal response of time element device 94 to any signal operating current which might be flowing through winding 88.
- 40 When the propulsion current is alternating current I provide the signaling current of a distinctly different frequency, as for example 25 cycle propulsion and 60 cycle signaling, and under propulsion current saturation conditions substantially similar effect is 45 produced in transformer 89 as with direct current propulsion—that is, as is well-known in induction apparatus design, the flux follows the current wave of the lower frequency 50 and the induced current flowing to the time element device would be that of the lower frequency. Under the conditions of using alternating current for propulsion, it is to be understood that time element device 94 55 would be non-responsive to the propulsion current frequency.
- 60 With the above description it should be clear that I have invented a unique means for controlling the time element device 94, 65 or equivalent device, by the entrance of a

train onto a track circuit and at the same time have introduced means whereby the motor controlling means 101 provides a superposed control of the same device automatically and without contacts and without 70 opening the circuit and further that my superposed control is continuously effective, and available for effect, from any point in the approach track circuit, and also that, as the control is established by the propulsion 75 current as a carrier current, it does not matter whether the train is controlled from one car or another in the train. It is to be understood that, in the operation of the controller 101, unless the excess predetermined 80 amount of propulsion current flows for a time period long enough for the time element device 94 to return to its inoperative condition, the time of operation of the time element 85 90 95 90 95 90 95 100 device 94, after the excess propulsion current is removed, will be accordingly lessened. The only influence of the return propulsion current flow, with respect to this particular invention, being, of course, to render the signaling current operation of the time element device 94, and the circuits controlled thereby, inert, inactive, and reactive.

The transformer 89 is designed to pass a certain quantity of propulsion current to allow for the operation of the car-lighting, 95 and car-compressor motor operating circuits and for any stray propulsion currents, due to the passage of trains on an adjacent track, or on the same track; and may further be arranged to allow a train to run with its 100 motors in series, in the track circuit, without cancelling or delaying the regular signal current operation of the time element device 94.

It will be noted that, the car-wheels 105 98—98^a and axle 99, in providing a shunt on the track relay to effect operation of the signal system in the rear, and in providing a shunt on that part of the track circuit which includes the source of power (transformer 10) and winding 88 whereby to effect 110 operation of the signal system in the advance, also acts to place that part of the track circuit which includes transformer 10 and winding 88 in multiple with said car-wheel 98—98^a axle 99 shunt so that, in the event of the general direction of the propulsion return current flow being opposite to that illustrated, the propulsion current voltage drop on said car-wheel shunt causes proportionate propulsion current flow in winding 88 of transformer 89, and from this follows the natural fact that, unless the circuit which provides propulsion current influence, to affect the superposed control of 115 the signal system in the advance, is continuously intact, there can be no train wheel shunt control operation to effect the non-superposed control of the signal system in 120 125 the advance.

At this time it is desired to point out that, since my super-posed control is carried into effect by virtue of winding 88 and transformer 89, it naturally follows that I may 5 arrange transmitter transformer 89 with a plurality of secondary windings 90 for the control of individual circuits and devices 94 and that a plurality of said transformers 89 may be connected in series or in parallel in 10 the same track circuit, each with or without a resistance 13 in multiple with primary winding 88.

The resistance 13, in addition to serving as a means to prevent short-circuit conditions 15 on transformer 10 when the train wheel shunt is adjacent wires 11 and 12 connection to the track circuit, also provides a means, by change in the value of resistance 13, for control of the propulsion current effect and 20 saturation influence in transformer 89 and, therefore, a specific design of transformer 89 is available for use with a great variety of propulsion current and track circuit conditions. Further, owing to the fact that the 25 magnetic circuit of transformer 89 is made up of thin laminated sheets a very simple and finely graduated means is available, by change in the number of laminations, to provide variation in the propulsion current influence on transformer 89 and without similarly affecting the regular signal current 30 operation of said transformer 89 and the circuits controlled thereby.

It is believed that the unique and novel 35 means underlying this invention have been clearly set-forth in the foregoing and the following description is intended to show the incorporation and embodiment of my invention in the control and operation of one 40 type of speed restricting signal system.

Referring to the drawing; it is presumed that a train has proceeded through the territory, in the direction of the arrow, and has stopped in block section 5 (presumably at a 45 passenger station) as shown. In accordance with proper practice the design of the signal system requires that a following train receive a stop indication, with the associated tripper arm in the tripping position, at a 50 point at least emergency braking distance in the rear for the maximum speed which the following train can attain, and, for the purpose of this description, it is assumed that said point is at signal 1¹ location and, accordingly, the control circuit for home relay 1^H (not shown but represented, in part, by the dotted line, commencing at energy 55 supply wire 28 and, thereafter, via contact (when closed) on track relay 5^T wire 106 contact on track relay 4^T wire 107 contact on track relay 3^T wire 108 contact on track relay 2^T wire 109 and thereafter, it will be understood, via contact on track relay 1^T (when closed), to the winding of home relay 1^H) is 60 open.

Now, it is entirely logical that, if the speed of the following train be reduced, said train may safely approach proportionately closer to the preceding train and, as this operation is allowable, means should be provided to 70 shorten the control of the signal in question, that the aspect may change and the tripper arm clear. This requires that a signal have more than one control (limit) and the variable length control circuits are 75 familiarly known in the art as "long and short controls". The short control is provided to be effective on the time-distance principle and is carried into effect by a time element device 94 (hereinbefore described) set in operation automatically by a train at a definite point. Now, in order that the short control 80 may become effective, it is necessary that the following train proceed at a speed within definite limits (usually within a given 85 track circuit) which will allow the time element device to act to provide the short control and this requires that the train (or some part of it) remain within the given distance (clearing section) for a definite time 90 (predetermined in accordance with the allowable speed for the given condition) and this is presumed to enforce the restriction for proper speed reduction; but reduced speed 95 does not necessarily result because the train may stop just inside the clearing section, wait for the time element device to act to provide the short control, and then accelerate to and pass the said time cleared signal at a speed considerably in excess of that intended and for this reason the short control must, 10 therefore, be long enough, in the existing systems, to take care of this actuality. Due to the above condition, extra length of short control is provided, in existing systems, and so increases the headway between trains, because the trains are thereby automatically spaced farther apart, and this makes for the net result of a limited total safe train capacity.

One of the principal objects of my invention is to reduce the above mentioned extra length of short control and thereby increase the train capacity of the railroad—and the specific means for accomplishing this will 11 now be described.

Assuming that the following train, represented by car-wheels 98—98^a and axle 99, has complied with the requirements of reduced speed in the block preceding signal 1¹, 12 that the shortened control, represented by dotted wire 110 made effective by the operation of the associated time element device (not shown but which is substantially similar in arrangement and operation to that 13 presently to be described in connection with the short control of signal 2¹) has provided for the clearing of signal 1¹ and the associated tripper arm and that said train has entered block section 1,

With the entrance of the following train (represented by car-wheels 98-98^a and axle 99) into block section 1, the train shunts the track circuit, in the usual manner, and due to the increased current flow from transformer 10 via winding 88 of transformer 89, an increased rate of induced current flow via winding 93 starts the operation of time element device 94, and, after the predetermined time, contact 97 closes whereafter energy flows from source 19 via power wire 17 wires 15 and 111 contact 97 wires 112 and 113 to wire 30 and thereafter via the control circuit for home relay 2^H (hereinbefore described) with consequent change in signal 2¹ aspect from red (stop) to yellow (caution) and clearing of the tripper arm 63. Thus, in effect, a by-pass is provided around the open track relay contact on track relay 5^T and this following train may proceed to signal 3¹—it having been previously determined (according to speed study design) that it was safe for the train to so proceed. Now, suppose that this train stops just within block section 1, waits until time element device 94 operates to clear signal 2¹ and tripper arm 63 and the motorman then operates controller 101 to accelerate the train. The very act of so doing (that is, to accelerate the train) causes the return propulsion current from the car motors (100) to saturate transmitter transformer 89 (as hereinbefore described) and cancels the signal current influence on time element device 94 and contact 97 opens and, the long control of signal 2¹ via contact on track relay 5^T being open, signal 2¹ yellow aspect (caution indication) will revert to the red aspect (stop indication) and tripper arm 63 will assume the tripping position—and this cycle of operation will automatically repeat responsive to all attempts on the part of the motorman to pass signal 2¹ at an excessive speed—intentional or otherwise. Exception to the above may be provided and incorporated in the design of transformer 89 (as hereinbefore described) to permit the motorman to operate the train with the motors "in series" without "setting the signal back" but this operation even then can only be carried out with full co-operation between the motorman and my superposed control system.

Obviously, even with my invention, the train may enter the clearing section and, due to a minus grade, coast and attain a speed somewhat higher than if the motorman, by braking, maintained or reduced the train speed; but this is a condition to which can be assigned a definite value in the design of signal location and requires far less increased spacing between trains than in the existing systems wherein the highest attainable power speed, at the time cleared

signal location must be assumed if safe conditions are to prevail. 65

If, instead of the train entering the clearing section in the manner (that is, coasting or running with less than a predetermined motor power) just above described, the train enters the clearing section with more train motor current flowing than is permitted in the signal system design, then the transmitter transformer 89 will be substantially saturated and not sufficiently responsive to the signal operating current and time element device 94 will be delayed in the start of its clearing operation, to provide the short control of signal 2¹, and, the long control being open, said train will be tripped at signal 2¹. 70 75 80

I have shown dash line 115 as representing the length of short control for signal 2¹ which would have to be provided in any similar "closing in" system which does not include my invention (hereinbefore described) for insuring that there will be no speeding of the (following) train in the clearing section, and it will be readily evident that whereas my invention has resulted in permitting said train to safely pass to signal 3¹—the existing type of similar system, with the short control necessarily extended through block section 5, could not act to clear signal 2¹, regardless of the speed of approach. To illustrate existing time relay control design, I have shown back contact 114 on track relay 1^T, it being understood that, without my invention, the time relay operation is started with the opening of track relay 1^T and, since a broken track wire or broken track rail in the track circuit (block section 1) will cause track relay 1^T to be open, it is readily evident that the entire time clearing of signals controlled by the track relay (1^T) will be "false clear" in existing systems—but with my superposed control this, comparatively stated, cannot happen because the continuous presence of the train wheel shunt is absolutely necessary to the time clearing of signals and stops by short control. 90 95 100 105 110 115

The dotted circuit wire 116 track relay contact on 4^T wire 117 track relay contact on 3^T wire 118 track relay contact on 2^T wire 119 and the associated short control clearing circuit wire 120 represents the home relay control circuit for the signal next in the rear of signal 1¹. Also wire 121 track relay contact on 5^T wire 122 track relay contact on 4^T wire 123 track relay contact on 3^T, (when closed) represents the circuit whereby energy may flow via wire 124 for the clearing of home relay 3^H and also that the circuit, wires 125, 128 and contact on home relay 2^H 120 125 provides the means whereby the distant relay 1^D (not shown) is cleared, all in the usual manner.

5 I have described the signal and automatic stop operation on long and short control, with respect to signal 2¹ and associated stop, and I desire it to be understood that signals 5¹, 3¹, 4¹, 5¹, and 6¹ etc. (when the speed study design, with reference to my invention, dictates their installation) would be similarly equipped and controlled.

10 Attention is directed to the fact that, even though I have illustrated and described the signal as of the light-type, the relays of the two-element two-position type, and the signal aspects controlled directly by the relays—it will be understood that the relays 15 may be of the single-element two or three position type, the signal of the semaphore type and that the tripper arm 63 constitutes one type of signal, and that the signal may be controlled direct by the automatic stop mechanism, all with the obvious appropriate changes well-known in this art.

20 While I have illustrated and described my invention as providing for the "setting ahead" and "setting back" of the next signal in advance (enforcing the caution indication) I desire it to be understood that, my invention may be applied to clearing the second signal in advance and thereby provide for "enforcing the proceed indication" 25 on the first signal in the advance and, at the same time, "enforcing the caution indication" on said second signal in advance, automatically by one and the same superposed control, and, also, that whereas I have shown 30 my superposed control as providing a short control two blocks shorter than the long control, it is to be understood that the short control may be brought into effect by shortening the long control by a fraction of a block, or by a plurality of block sections, 35 all in accordance with the specific design.

40 It is specifically pointed out that, when only a short control is provided, the signal would be classed as a normal danger signal with the block control normally open and my superposed control enforces a restricted speed in the approach to the instant signal, by setting the signal ahead, and again setting it back if the prescribed speed of approach 45 is violated.

50 In any case, it is to be noted that, the "set ahead" or change to less restrictive indication is entirely dependent on the continuous presence of signaling current under the proper conditions and that the "set ahead" indication can only be retained under sustained similarly proper conditions.

55 Also, it is to be noted that, the propulsion current can only act to provide a "set back" or more restrictive indication and that the propulsion current flow, when producing "set back" or "hold back" conditions, acts independently of any and all signaling current "set ahead", or otherwise, operation.

65 Owing to the fact that, the short control,

when operative in this type of closing in system, is effective to only by-pass the far end of the long control, it will be evident that all restrictions providing and retaining the short control will be instantly and automatically 70 cancelled when the long control is cleared and that, this cancellation will take place regardless of where the following train may be or what part or parts of the cycle for short control operation may have been completed. 75

Hereinbefore, I have portrayed my invention as providing a short control of a long controlled home relay and thereby "enforced a caution indication" but it will be understood that I may leave the long control unaffected and apply my superposed control to the distant relay control circuit and "enforce a proceed indication independently of enforcing a caution indication. 85

As has been explained, excess territory must be added to existing system short controls to provide emergency braking distance for a maximum speed condition, which may frequently happen, on the part of the following train, and which added territory results to increase the headway of every train operated, but with my superposed control said excess territory is subtracted and only added (in setting back of the signal) in my system 95 for the train which violates—intentionally or otherwise—its speed of approach and, excepting which, therefore, my superposed control permits minimum headway between all trains operated. 100

It is believed that, the hereinbefore description, clearly portrays my invention with the end in view that, therein I have provided a signaling system entirely automatic in character and which compares very closely and favorably with what is termed "hand signaling" and better or more efficient than which no signaling system could hope to be—if the human element involved in hand signaling were (or could be made) 105 thoroughly dependable. 110

Particular economies result in the use of my superposed control system because (a) as the possible speed of a following train can be controlled within definite limits, fewer 115 block sections are necessary to the safe accomplishment of a minimum headway and (b) fewer blocks are necessary to the safe accomplishment of any given headway; and therefore the first cost and also the maintenance cost are proportionately less. 120

Obviously, the foregoing illustration and descriptions, do not exhaust the many modifications and ramifications in railway signal circuit work, which I have made, and which anyone ordinarily skilled in the art, would make under the varied conditions obtaining in this art and, therefore, I desire it to be understood that the specific arrangement shown has been selected for illustratory pur- 125 130

poses rather than to show the scope of my invention which may be modified and changed without departing from the spirit and scope of the broad idea of means underlying my 5 present invention.

I claim:

1. The method of governing train movements on a railway track equipped with an 10 automatic wayside block signal system with long and short control circuits therefor; which method provides that a restricting signal in advance will be governed by the short control automatically by an approaching 15 train consuming a predetermined time over a prescribed track section and which method also provides that said signal, which has so been operatively governed, will be governed by the long control in the event that said train does not thereafter consume 20 a predetermined time over the remainder of said prescribed track section.

2. The method of limiting the speed of an 25 approaching train on a railway track equipped with an automatic wayside block signal and train stopping system with long and short control circuits therefor; which method provides that a restricting signal and its associated train tripping device in 30 advance will be governed by the short control automatically by an approaching train consuming a predetermined time over a prescribed track section and which method also provides that said signal and tripping device, which has so been operatively governed, will be governed by the long control in the event that said train does not thereafter consume 35 a predetermined time over the remainder of said prescribed track section, said wayside tripping device cooperating 40 with train carried means for braking said train.

3. The method of governing electrically 45 propelled train movements on a railway track equipped with an automatic wayside block signal and train stopping system with long and short control circuits therefor; which method provides that a restricting signal and its associated train tripping device in advance will be governed by the short control automatically by an approaching 50 train consuming a predetermined time over a prescribed track section; which method also provides that the operation by the short control will be cancelled by virtue of propulsion current flow through the train propelling 55 motors.

4. The method of governing electrically 60 propelled train movements on a railway track equipped with an automatic wayside block signal and train stopping system with long and short control circuits therefor; which method provides that a restricting signal and its associated train tripping device in advance will be governed by the short

control automatically by an approaching 65 train coasting and consuming a predetermined time over a prescribed track section; which method also consists in withholding said operation by the short control if the train motors are energized at the time of 70 entrance of said train into said prescribed track section.

5. The method of governing electrically 75 propelled train movements on a railway track equipped with an automatic wayside block signal and train stopping system with track circuits and long and short control circuits therefor; which method provides that a restricting signal and its associated train tripping device in advance will be governed 80 by the short control automatically by an approaching train coasting over a prescribed section of track circuit; which method also consists in withholding operation by the short control if the train motors are energized at the time of entrance of said train into said prescribed track section and which short control will be withheld as long as 85 propulsion current flows through said track circuit which normally provides said short control operation.

6. The method of governing electrically 90 propelled train movements on a railway track equipped with an automatic wayside block signal and train stopping system including track circuits therefor; which method provides that a restricting signal and its associated train tripping device in advance will be governed automatically by 95 an approaching train coasting and consuming a predetermined time over a prescribed section of track circuit; which method also provides that the operation of said system will be withheld or cancelled if and when more than a predetermined amount of propulsion current from the train motors flows 100 via the track circuit which provides for said operation of said system.

7. In a railway traffic controlling system, 105 a track circuit including a source of energy and a track relay, and a time element inductively coupled to said track circuit.

8. In a railway traffic controlling system, 110 a track circuit including a source of energy and a track relay, and a time element relay inductively coupled to said track circuit, said time element relay controlling the signal of an advance block.

9. In a railway traffic controlling system, 115 a track circuit including a source of energy, and time element means continuously inductively coupled to said track circuit, said time element means controlling the signal of an advance block.

10. In a railway traffic controlling system, 120 a track circuit including a source of energy, and time element means coupled to said track circuit, said time element means re-

sponsive to increased current flow in said track circuit, for controlling a winding of a two-element relay of an advance block.

11. In a railway traffic controlling system, a track circuit including a source of energy, and a winding inductively coupled to said track circuit, said winding adapted to induce current into a circuit including a winding of a time element device when said track circuit is occupied by a train.

12. In a block signal system, an electrical time element device inductively coupled to a track circuit, said element controlling a block signal in the advance territory.

15. 13. A railway traffic controlling system comprised of a series of blocks; characterized by the time element control of a signal in an advance block being governed by an increase of track circuit energy in an approach track circuit.

20. 14. In a railway traffic controlling system including a track section and an electric circuit traversing said section, a reactive device included in series in said electric circuit, and a time element inductively coupled with said reactive device.

30. 15. In a railway traffic controlling system, a track circuit including a source of energy and a track relay, and a time element device continuously inductively coupled to said track circuit.

35. 16. In a railway traffic controlling system, a track and circuit adapted for the operation of electrically propelled trains, a source of energy therefor, a train including train carried propelling motors, a motor controller and a brake system adapted to be influenced by wayside apparatus, an alternating current track circuit including a source of energy and a track relay, said track relay controlling an automatic wayside block signal and train stopping system, and an inductive coupling adapted to be influenced by both sources of energy and incorporated in the energy supply to the track circuit, said inductive coupling arranged to provide train wheel shunt control of an advance block signal and train stopping device.

40. 17. The invention set forth in claim 16 with the signal and train stopping system comprised of long and short control circuits, said block signal and train stopping system in advance operating on the long control when more than a predetermined amount of propulsion current flows through the inductive coupling, said block signal and train stopping system in advance operating on the short control by virtue of a train approaching on a predetermined time-distance principle when less than said predetermined amount of propulsion current flows through said coupling.

45. 18. The invention set forth in claim 16, said inductive coupling arranged to provide control of an advance block signal and train

stopping device by the train carried motor controller.

19. In a railway traffic controlling system, a track and circuit including a source of energy therefor adapted for the operation of electrically propelled trains, a train including train carried propelling motors and a motor controller for propelling said train, a brake system for said train, said brake system adapted to be influenced by wayside co-acting apparatus, an alternating current track circuit including a source of energy and a track relay, said alternating current track circuit making joint use of said track and circuit, said track relay controlling an automatic wayside block signal and train stopping system, and means including a time element device adapted to provide train wheel shunt control of an advance block signal and train stopping device by said train, said means acting independently of said track relay.

20. The invention set forth in claim 19, said means also including an inductive coupling incorporated in the second mentioned circuit and adapted to control said time element device.

21. The invention set forth in claim 19, said means also including an inductive coupling incorporated in the second mentioned circuit and adapted to induce operating current into the circuit of the time element device provided less than a predetermined amount of the train propelling current flows through one winding of said inductive coupling.

22. The invention set forth in claim 19, said means also including an inductive coupling incorporated in the second mentioned circuit and adapted to induce operating current into the circuit of the time element device provided less than a predetermined amount of the train propelling current flows through one winding of said inductive coupling, more than said predetermined amount of train propelling current flow acting to nullify said operating current.

23. The invention set forth in claim 19, said means also including an inductive coupling incorporated in the second mentioned circuit and having a resistance in shunt with the primary winding of said inductive coupling.

24. The invention set forth in claim 19, said means also including an inductive coupling one winding of which is included in the second mentioned circuit and having a resistance in shunt therewith, the other winding of said coupling controlling a relay, said relay controlling said time element device.

25. The invention set forth in claim 19, said means also including an inductive coupling one winding of which is included in the second mentioned circuit and having a resistance in shunt therewith, another winding

of said coupling controlling a relay, said relay controlling said time element device, said coupling adapted to be effectively operative when the track circuit is shunted and to be effectively inoperative when more than a predetermined amount of train propelling current flows therein.

26. The invention set forth in claim 19, said means also including an inductive coupling one winding of which is included in the second mentioned circuit, another winding of said coupling controlling a relay, said relay controlling delayed action contacts in the control circuit of an advance block signal and train stopping device, said coupling adapted to be effectively operative when the track circuit is shunted and to be effectively inoperative when more than a predetermined amount of train propelling current flows via said one winding.

27. A railway signal circuit controller comprising an inductive coupling one winding of which is included in series in an energy supply wire to an alternating current track circuit, another winding of said coupling included in a circuit including a control relay, said relay adapted to be responsive to train wheel shunt control provided less than a predetermined amount of train propulsion current flows through said one winding.

28. The invention set forth in claim 27 with said one winding having a resistance in shunt therewith.

29. A railway signal circuit controller comprising a plurality of inductive couplings one winding of each of which is included in an energy supply wire to an alternating current track circuit, another winding of each coupling included in a circuit including a control relay, said relay adapted to be positively responsive to train wheel shunt control when said track circuit is occupied.

30. The invention set forth in claim 29, said relay adapted to be positively responsive to train wheel shunt control provided less than a predetermined amount of train propulsion current flows through said one winding.

31. The invention set forth in claim 29, each of said one windings having a resistance in shunt therewith.

32. The invention set forth in claim 27, with said relay actuating delayed action contacts.

33. The invention set forth in claim 27, with said relay comprised of two windings one of which is included in circuit with said other winding of said inductive coupling and the other of said two windings permanently connected to a source of energy of similar characteristics as the track circuit energy supply.

34. The invention set forth in claim 27,

with said relay also adapted to be non-responsive to said train wheel shunt control when more than a predetermined amount of train propulsion current flows through said one winding.

70

35. The invention set forth in claim 27, with said inductive coupling arranged with an adjustable magnetic circuit whereby to adjust the coupling for propulsion current influence without substantially affecting the signal current influence.

36. The method of governing train movements on a railway track equipped with an automatic wayside train stop system with long and short control circuits therefor: which method provides that a restricting train stop in advance will be governed by the short control automatically by an approaching train consuming a predetermined time over a prescribed track section and which method also provides that said train stop, which has so been operatively governed, will be governed by the long control in the event that said train does not thereafter consume a pre-determined time over the remainder of said prescribed track section.

37. The method of limiting the speed of an approaching train on a railway track equipped with an automatic wayside train stopping system with long and short control circuits therefor: which provides that a restricting train tripping device in advance will be governed by the short control automatically by an approaching train consuming a predetermined time over a prescribed track section and which method also provides that said tripping device, which has so been operatively governed, will be governed by the long control in the event that said train does not thereafter consume a predetermined time over the remainder of said prescribed track section, said wayside tripping device cooperating with train carried means for braking said train.

38. The method of governing electrically propelled train movements on a railway track equipped with an automatic wayside train stopping system with long and short control circuits therefor: which method provides that a restricting train tripping device in advance will be governed by the short control circuit automatically by an approaching train consuming a predetermined time over a prescribed track section: which method also provides that the operation by said short control circuit will be cancelled by virtue of propulsion current flow through the train propelling motors.

39. The method of governing electrically propelled train movements on a railway track equipped with an automatic wayside train stopping system with long and short control circuits therefor: which method provides that a restricting train tripping de-

vice in advance will be governed by the short control circuit automatically by an approaching train coasting and consuming a predetermined time over a prescribed track section: which method also consists in withholding operation by said short control circuit if the train motors are energized at the time of entrance of said train into said prescribed track section.

- 10 40. The method of governing electrically propelled train movements on a railway track equipped with an automatic wayside train stopping system with track circuits and long and short control circuits therefor: 15 which method provides that a restricting train tripping device in advance will be governed by the short control circuit automatically by an approaching train coasting over a prescribed section of track circuit: which 20 method also consists in withholding operation by said short control circuit if the train motors are energized at the time of entrance of said train into said prescribed track section and which short control circuit will be withheld as long as propulsion current flows 25 through said track circuit which normally provides said short control operation.

- 30 41. The method of governing electrically propelled train movements on a railway track equipped with an automatic wayside train stopping system including track circuits therefor: which method provides that a restricting train tripping device in advance will be governed automatically by an 35 approaching train coasting and consuming a predetermined time over a prescribed section of track circuit: which method also provides that the operation of said system will be withheld or cancelled if and when more than a predetermined amount of propulsion current from the train propelling motors flows via the track circuit which provides for said operation of said system.

- 40 42. In a railway traffic controlling system, a track circuit including a source of 45 energy, and time element means continu-

ously inductively coupled to said track circuit, said time element means controlling the automatic train stop of an advance section.

50 43. In a train stop system, an electrical time element device inductively coupled to a track circuit, said element controlling a train stop in advance territory.

55 44. A railway traffic controlling system comprised of a series of track sections: characterized by the time element control of a train stop in an advance section being governed by an increase of track circuit energy 60 in an approach track circuit.

65 45. In a railway traffic controlling system, a track circuit including a source of energy and a track relay, and a time element device, said time element device connected in series in said circuit and arranged to time element 70 control the signal of an advance block.

75 46. The invention set forth in claim 45, with said time element device continually energized but inoperative to effect said control when said track circuit is not occupied by a 80 train and operative to exercise said control when said track circuit is occupied by a train.

85 47. In a railway traffic controlling system, a track circuit including a source of energy, and a time element device, said time element device connected in series in the energy supply to said track circuit and arranged to time element control the signal of an advance block.

90 48. The invention set forth in claim 47, with said time element device continually energized but inoperative to effect said control when said track circuit is not occupied by a train and operative to exercise said control when said track circuit is occupied by a train.

95 Signed at Brooklyn in the county of Kings and State of New York this 24th day of March A. D. 1926.

GILBERT C. WHITNEY.
